UNITED STATES PATENT OFFICE.

JOHN H. REYNOLDS, OF TROY, AND GREGORY GERDOM, OF WEST TROY,
NEW YORK; SAID GERDOM ASSIGNOR OF ONE-FIFTH HIS RIGHT TO
SAID REYNOLDS.

CAR-BRAKE.

SPECIFICATION forming part of Letters Patent No. 393,722, dated November 27, 1888.

Application filed September 18, 1888. Serial No. 285,672. (No model.)

To all whom it may concern:

Be it known that we, JOHN H. REYNOLDS, of Troy, in the county of Rensselaer and State of New York, and GREGORY GERDOM, of West 5 Troy, in the county of Albany and State of New York, have invented certain new and useful Improvements in Car-Brakes, of which the following is a specification.

Our invention relates to improvements in 10 brake mechanisms for railway-cars; and the object of our improvements is to provide facilities for utilizing the momentive power of the moving cars for the purpose of operating the brakes. This object we attain by the mechanism 15 illustrated in the accompanying drawings, which are herein referred to, and form part of this specification, and in which—

Figure 1 is an inverted plan view of the bottom framing of a car containing our invention, and Fig. 2 is a longitudinal section of the same at the line X X.

As represented in the drawings, A is the bottom frame of a car, which frame-work may be varied in any manner to suit the purpose 25 for which the car may be designed; B, the car-wheels, secured in the usual manner to the axles C and C'; D, a hollow or outer friction-cone (shown in section in Fig. 1) provided with an elongated hub, 1, and secured to the 30 axle C; E, an inner friction-cone fitted to slide into and engage in frictional contact with the hollow friction-cone D. The cone E is loosely fitted onto the hub 1, so as to permit the latter to revolve freely in the hub 2 of the cone 35 E. The latter is provided on its outer face with a stud, 3, fixed therein or formed thereon, as may be preferred, and to said stud one end of a chain, F, is secured. The opposite end of said chain is connected by links 4 to 40 opposite ends of a friction-band, G, which surrounds a grooved friction-wheel, H, that is secured to the axle C'.

A collar, I, is secured to the axle C at sufficient distance from the hub 1 of the cone E to 45 permit the two wedge-pieces J, when either or both of the latter are drawn back, to lie in the space between the collar I and hub 2 without crowding the cone E into the cone D. The wedge-pieces J are bifurcated to span the axle 50 C, or, when preferred, the hub 1, so that each wedge-piece will have one limb above and an-

other below said axle, and by this distribution of the limbs we counteract any tendency of the collar I and hub 2 to draw said wedge-pieces inwardly when they (the wedge-pieces) are moved 55 into frictional contact with said collar and hub. The two wedge-pieces J are arranged in reversed directions, as shown in Fig. 1, and each is provided with a rod, 5, which forms a component part thereof. Said rods extend toward 60 opposite ends of the car, where each is connected to its appropriate hand-lever K, so that each of said levers can only operate the wedge-piece to which it is connected. The hand-levers K are each provided with a graduated 65 quadrant, L, so that the degree of frictional contact between the friction-cones D and E can be varied to suit the occasion.

The operation of our brake mechanism is as follows: While the wedge-pieces J are drawn 70 back, as shown in Fig. 1, the friction-cone E will remain separated from the cone D, so that wheels B can revolve freely without affecting the braking mechanism; but when it becomes necessary to apply the brakes by moving 75 either of the levers K to force its connected wedge-piece J inwardly, so that it will coact with the opposite wedge-piece to force the cone E into frictional contact with the cone D, the cone E will instantly begin to revolve with 80 the axle C, and thereby the chain F will be drawn to close the band G snugly around the friction-wheel H, until, by the shortening action of said chain, produced by the rotations of the cone E, sufficient resistance is developed 85 to stop the wheels B from revolving. By drawing the wedge-piece J back to its normal position the cones D and E will be separated and the wheels B will be at liberty to revolve.

We are aware that friction-couplings have 90 heretofore been employed for operating brake mechanisms on railway-cars; but in such prior constructions said couplings have been combined with other intermediate instrumentalities differing in their construction and mode 95 of operation from the combination of parts herein shown and described. We do not broadly claim the use of friction-couplings for operating car-brakes; but

We claim as our invention—

1. In a car-brake, the combination of a friction-coupling having one of its cones secured

to one of the axles of the car, the complementary cone of said coupling being loosely fitted on said axle and connected to a friction-band, which is fitted to clamp around a friction-wheel 5 secured to an adjacent axle of the same car, and a wedging mechanism, which is fitted to slide between the loose cone of the friction-coupling, and a collar secured to the axle which carries said coupling, as and for the purpose 10 herein specified.

2. In a car-brake, the combination of a friction-cone, D, and a collar, I, both secured to the axle C, a loose friction-cone, E, adapted to engage in frictional contact with the cone D,

a friction-wheel, H, secured to the axle C' and 15 provided with a clamping-band, G, which is connected to the cone E, the oppositely-arranged wedge-pieces J, interposed between the cone E and collar I and adapted to force the cone E into frictional contact with the cone D, 20 and the operating-levers K, connected to said wedge-pieces, as and for the purpose herein specified.

JOHN H. REYNOLDS.
GREGORY GERDOM.
